UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

FOCUSING MECHANISM.

1,229,177.

Specification of Letters Patent.

Patented June 5, 1917.

Application filed December 30, 1916. Serial No. 139,915.

To all whom it may concern:

Be it known that I, CHARLES E. GODLEY, a citizen of the United States, and residing at Detroit, in the county of Wayne and State of Michigan, have invented a new and Improved Focusing Mechanism, of which the following is a specification.

This invention relates to means for focusing electric light bulbs within the reflectors of lamps of the automobile-headlight type, and its object is to produce a device of this kind that is completely detachable, that may be quickly and easily installed without the use of any tools, and which can be constructed at low cost.

This invention consists, in combination with the casing or body of the lamp formed with a central boss at its rear end and a reflector therein having a central cylindrical 20 guide for a lamp-bulb socket, of a resilient support adapted to hold the focusing device in central position by engaging the inner walls of the boss on the lamp casing, a screw carried by the support and having a 25 head which is revolvably mounted in a perforation in the center of the boss, and a bar 30 slidably mounted on the support, one end of the bar connected to the lamp-bulb socket and the other being turned up and fitted to receive the adjusting screw. It further consists in the resilient means for guiding said 35 bar on the support and in the details of construction illustrated in the accompanying drawings and particularly pointed out in the claims.

In the accompanying drawing, Figure 1 is a central longitudinal section of a lamp equipped with this improved focusing device. Fig. 2 is a side elevation of the focusing device and Fig. 3 is a front elevation of the rear end thereof. Fig. 4 is a bottom plan view of the sleeve on the reflector.

Similar reference characters refer to like parts throughout the several views.

The lamp body or casing 1, having a boss 2 spun onto its rear end, the reflector 3 having a rearwardly extending cylindrical sleeve 4, the door ring 5, the lens 6 and the cork cushion 7 back of it, and the bulb 8 form no part of the present invention. Slidable in the sleeve 4 is a lamp-socket 9 having terminals 10 to connect to the circuit wires for the lamp. The sleeve 4 is formed with a notch 11 in its lower side to permit the bar

12, which is connected to the socket 9, to 55 slide back and forth. The socket is longitudinally slidable in the sleeve 4 and is prevented from turning by the bar 12 fitting in the notch 11.

The supporting means for the rear end of 60 this focusing device is preferably formed from a resilient sheet of metal and consists of the two connected side members or arms 15 and the bottom member 16 which is provided with upwardly extending flanges 17 65 which prevent the bar 12 from moving laterally. The bar rests on the bottom 16 and may be pressed against this bottom by means of a resilient wire clip 18, as shown in Fig. 3. The two arms 15 are so formed 70 that they will fit within the boss 2 on the casing and be held firmly in position therein. It will be noticed that the casing is formed with an internal rib or bead at the line of connection between the boss and the main 75 part of the casing, behind which certain shoulders formed by bending the arms 15 engage to hold this resilient support in position. Because of this peculiar conformation of the support and of the interior of 80 the casing, the middle part of the support is pressed rearwardly toward the middle portion of the boss.

The adjusting member of this device consists of a flat bar which is twisted to constitute a screw 20 of very coarse pitch which extends through a slot in the upturned end 21 of the bar 12. A small pin 22 prevents the screw disengaging from the end of the bar. On the rear end of the screw is a head 23 having a reduced portion 24 that is journaled in a hole in the supporting member and a second reduced portion 25 that is journaled in an aperture in the center of the boss 2. This head is preferably provided with a notch 26 to receive a flat tool or the edge of a small coin by means of which the screw may be turned and the lamp-bulb moved in or out relative to the reflector as desired.

By removing the reflector and pressing the ends of the parts 15 of the supporting device toward each other, the focusing device can be entirely removed from the lamp casing. The pressure normally exerted between the head 23 and the boss on one side and the spring on the other side is sufficient to keep the screw from being turned by the

jars and jolts of the vehicle on which the lamp is mounted. No rivets or screws are necessary to hold the parts in position, which reduces the cost of assembling this 5 structure to a minimum.

While the hole in the boss 2 through which the part 25 on the button 23 extends needs not necessarily be co-axial with the socket 9, it is preferably so in order that 10 the reflector may be inserted without attention to its angular position.

I claim:

1. In a focusing device for a lamp having a casing and a reflector mounted therein, a lamp socket slidable in the reflector, a screw revolvably mounted in the casing, a spring to hold the screw in position formed from a flat piece of resilient metal bent to fit the casing and provided with a hole to 20 permit the screw to pass through it, and means engaging the screw and socket to permit the screw to focus the lamp bulb.

2. In a focusing device, the combination of a cup-shaped lamp casing and a reflector 25 mounted therein, a cylindrical guide projecting rearwardly from the reflector, said casing being formed with a boss opposite the open end, a resilient support within the boss, a screw carried by the support, a 30 bulb-socket slidable in the guide on the reflector, and a bar connected to the socket and having an upturned end engaged by the screw.

3. In a focusing device, the combination 35 of a cup-shaped lamp casing having a boss opposite its opening, said boss being provided with a circular hole, a reflector mounted in the casing and provided with a cylindrical guide, a bulb-socket slidable 40 in said guide, a rearwardly extending bar connected to said socket and having its rear end upturned to cross the central line of the reflector and socket, said guide having a notch to receive the forward end of said 45 bar to prevent the socket from turning, and a screw having a head revolvble in the hole in the boss and a body engaging with the upturned end of the bar.

4. In a focusing device, the combination 50 of a cup-shaped lamp casing having a boss opposite its opening, said boss being provided with a circular hole, a reflector mounted in the casing and provided with a cylindrical guide, a bulb-socket slidable in 55 said guide, a rearwardly extending bar connected to said socket and having its rear end upturned to cross the central line of the reflector and socket, said guide having a notch to receive the forward end of said

bar to prevent the socket from turning, a 60 screw having a head revolvble in the hole in the boss and a body engaging with the upturned end of the bar, and resilient means 65 detachably mounted within said boss to support said bar and hold the head of said screw in position in said hole.

5. In a focusing device, the combination of a cup-shaped lamp casing having a boss opposite its opening, the casing having a reentrant bead at the line of attachment of 70 the boss to the main part of the casing, a cup-shaped reflector mounted in the casing and having an opening in its rear end, a lamp-bulb socket slidable in said opening in the rear end of the reflector, a bar connected to said socket, a focusing screw engaging said bar to move it longitudinally, and a resilient support for the bar and screw having members engaging said reentrant bead to hold the parts in position. 80

6. In a focusing device, the combination of a cup-shaped lamp casing having inwardly extending projections, a reflector mounted in the casing and provided with an opening in its rear end, a lamp socket 85 slidable in said opening in the reflector, a resilient support detachably engaging the projections on the casing, and an adjustable connection between the support and the socket to move the socket longitudinally. 90

7. In a focusing device, the combination of a cup-shaped lamp casing provided with a boss opposite its open end and with an interior rib at the line of connection between the boss and the main part of the 95 casing and also provided with a circular hole in the boss, a reflector mounted in the casing and having a circular hole, a bulb-socket slidable in said hole in the reflector, a rearwardly extending bar connected to 100 the socket and having an upturned end provided with an elongated hole, a helically twisted rod extending through said hole and adapted to move the bar back and forth when turned, a head on said screw revolvably mounted in the hole in the boss, a resilient supporting member having oppositely extending arms engaging the rib in the casing and engaging the head on the screw at the juncture of said arms to press the head into the hole in the boss and also having a bottom portion extending forwardly to form a support for the rear end of the bar, the edges of the bottom being bent up to form guides for the bar, and resilient means to hold the bar in position between said guides. 110

CHARLES E. GODLEY. 115
